INTERNAL GRINDING MACHINE

Harold L. Blood, Worcester, Mass., assignor to
 The Heald Machine Company, Worcester, Mass.,
 a corporation of Massachusetts

Application April 5, 1939, Serial No. 266,163

12 Claims. (Cl. 51—103)

The present invention relates to internal or bore grinding by the so-called chuckless or centerless method, involving support and rotation of a hollow workpiece by rolling contact with its outer peripheral surface, so that the internal grinding operation generates a bore which is truly concentric with said outer surface. More particularly, the invention resides in a machine organization of this centerless type adapted especially to the handling and internal grinding of 10 hollow workpieces having tapered or contoured (non-cylindric) outer peripheral surfaces.

Heretofore in the centerless internal grinding of such non-cylindric hollow workpieces, the practice as disclosed for example in Cramer Patent No. 2,176,248, dated Oct. 17, 1939, has been to engage the work, for support and rotation thereof, in much the same manner as is customary in the centerless internal grinding of cylindric work of uniform outside diameter,—using rolls or wheels having their axes substantially parallel to the grinding wheel and workpiece axes, and using a solidly-mounted thrust-resisting member for one end of the workpiece to bear against.

Such an arrangement has definite limitations, 25 in that it is not readily adjustable to non-cylindric work of different sizes and of varying external tapers or contours; one object of my invention is to overcome these difficulties.

A further object of my invention is to so arrange the thrust-resisting element of the centerless workholding means that it not only promotes and assures the latter's drive of the workpiece, but also serves to compensate automatically for slight variations in external dimension that may be encountered in presenting a succession or group of similar externally tapered workpieces to the machine, in such manner that their bores, despite such size variations, can be maintained in substantial axial alignment with the sizing gauge which is customarily employed and incorporated in such a machine.

Other and further objects and advantages of the present invention will hereinafter more fully appear from the following detailed description taken in connection with the accompanying drawings, in which—

Fig. 1 is a front elevation of a machine embodying the invention, with parts broken away.

Fig. 2 is a larger scale plan view of the work-supporting and work-rotating means.

Fig. 3 is a sectional view substantially along the line 3—3 of Fig. 2.

Fig. 4 is a sectional view substantially along the line 4—4 of Fig. 2.

Fig. 5 is a fragmentary front elevation of a part of the work-supporting structure.

Like reference characters refer to like parts in the different figures.

As shown in Fig. 1 the machine to which my invention is applied is a conventional type of internal grinding machine having the usual reciprocating table 1 on which either the grinding wheel or the work to be ground is carried, the reciprocations of the table serving in either case to produce a relative translatory movement between the grinding wheel and the workpiece. In the machine shown, the table supports and carries a workhead 2 while the wheelhead 3 is mounted on a bridge 4 which spans the guideways 5, Fig. 3, provided by the machine base 6 for the movements of the table 1. The grinding wheel 7 is carried on a spindle 8 journalled in the wheel head and is suitably rotated at a high rate of speed. The workpiece *a*, see also Figs. 2, 3 and 4, is adapted to be rotated in grinding position by a centerless or chuckless work-holding arrangement provided by the work-head, as will hereinafter appear.

20 The reciprocations of the table 1 which cause the rotating grinding wheel to make the desired traverse longitudinally, through the bore of the workpiece *a*, and which provide for an axial separation between the wheel and workpiece, are imparted in any well known manner, as by the use of the table controlling and reversing mechanism described in detail in the Blood and Burns Patent No. 2,027,627, dated January 4, 1936. This mechanism is not a feature of the present invention and need not be here described in detail.

25 The crossfeed movement between the workpiece and the grinding wheel may be obtained by a transverse movement of the wheelhead 3 on the bridge 4. This crossfeed movement may be procured by any well known means, as for example, the fluid pressure actuated crossfeed mechanism of the Blood and Burns Patent No. 2,027,627, above referred to. It is sufficient to note that a cross slide, not shown, carrying the wheelhead is horizontally movable on the bridge and is shifted by a crossfeed screw 9 which is rotated by a rack 10 reciprocated by a suitable fluid pressure actuated means.

30 The table 1 also carries a suitable truing or dressing tool 11 for the grinding wheel; the operation of this tool is also conventional in character and need not be described in detail.

35 The illustrated machine also incorporates a well known form of gaging mechanism by which the grinding operation on the bore of each suc-

cessive workpiece *a* is automatically controlled, this gaging mechanism being substantially of the same type as that disclosed in the aforesaid Blood and Burns Patent 2,027,627 and embodying, among other things, a suitable bracket 12, projecting upwardly from the table 1 for the slidable support of a gage rod 13 substantially in axial alignment with the workpiece *a*; it is sufficient to note for present purposes that the rod 13 carries gage members 14 and 15, slightly differing in diameter, which are urged yieldingly in the direction of the workpiece bore as the grinding operation thereon proceeds; when the workpiece bore is enlarged sufficiently for the smaller of these gage members to enter it, there occurs automatically, as described in said Blood and Burns patent, dressing and truing of the grinding wheel by the tool 11, following which the grinding operation is resumed until the larger of the gage members can enter said bore, whereupon with the latter brought to the desired size, the grinding operation is discontinued.

The present invention provides a readily adjustable centerless or chuckless work-supporting means so arranged that the hollow work, regardless of variations in size, can be supported and rotated in substantial axial alignment with this gaging mechanism. The work-supporting and work-rotating elements are particularly adapted to workpieces having tapered or contoured external peripheries such as illustrated by the workpiece *a* in Figs. 1 and 2, the same representing the inner cone raceway member of a roller bearing having a frusto-conical outer surface with flanges at each end. For the centerless support of such a workpiece, I provide, as shown in Figs. 2 and 3, the three adjustable elements 16, 17 and 18, adapted to engage with the frusto-conical surface of said workpiece. The element 16 is a driven rotary wheel or roll, for imparting rotation to the workpiece, and preferably engaging its outer surface substantially in opposition to the engagement of the grinding wheel 1 with the workpiece bore; the element 17 is arranged so as to provide, in cooperation with the element 16, a work-receiving throat; and the third element 18, as is here shown as a pressure roll or wheel which, as hereinafter described, is held yieldably against the external tapered surface of the workpiece to retain the latter in said work-receiving throat.

The backing or regulating roll 16, Fig. 2, is mounted on the end of a spindle 16a journalled in a housing 19, and the spindle is driven from a motor 20, the pulley 21 of which is connected by a belt 22 to a pulley 23 on the spindles 16a. The housing 19 and motor 20 are mounted on a base plate 24 which is angularly adjustable on a pin 25. The pin 25 projects vertically from a slide 26 positioned beneath the base plate. This slide has guideways on the underside thereof engageable with corresponding transversely extending guides 27 on the table 1. The position of the slide 26 transversely of the table is adjusted by means of a screw 28, Fig. 3, suitably held against endwise movement on the table and engaging a threaded lug, not shown, on the underside of the slide. The angular position of the base plate 24 is maintained, when once adjusted, by a clamping screw 29 in a lug 30 which extends upwardly from the slide and engages an arcuate surface 24' on the underside of the base plate.

As shown in Fig. 4, the supporting element 17 is carried by a block 31 in which it is vertically adjustable, being held in adjusted position by a

clamping screw 32. The block 31 is bolted to a small cross slide 33, the position of which, transversely of the table, is controlled by an adjusting screw 34.

5 The pressure roll 18 is journalled on a spindle 18a provided by a housing 35 mounted on a base plate 36. The latter is turnable on a pin 37 carried by a turntable 38, whose upper surface provides a support for the angular movement of said plate 36. The turntable 38 has an upwardly extending lug 38' in which is positioned an adjustable screw 39 engageable by the plate 36 to limit the movement of the pressure roll 18 toward the workpiece. This movement of the pressure roll 10 15 against the workpiece surface is obtained by the coil spring 40 connecting the housing 35 to any suitable projection of the table 1, and thus serving to yieldably draw the roll 18 against the workpiece. A handle 41 provides for manual turning 20 of the housing about the axis of the pin 37.

The angularity of the axis of the pressure roll 18 relative to the workpiece axis is adjusted by 25 pivotal movement of the turntable 38 about a pin 42 carried by a slide 43 which is transversely adjustable on the table 1. The slide 43 has an upwardly extending lug 43' having a clamping screw 45 which holds the turntable against turning movement relative to the slide. The position 30 of the slide 43 transversely of the table 1 is adjusted by means of a screw 46 held against endwise movement on the table 1 and engageable with a threaded portion, not shown, of the slide 43.

35 The above-described arrangement is readily adjustable so as to accommodate workpieces of different sizes and to hold and rotate them in axial alignment with the gaging mechanism of the machine. This accommodation to different sizes of workpieces is obtained by operation of the screws 28 and 46 to procure inward movement or outward movement as desired of the slides 26 and 43 respectively; also by the vertical and horizontal adjustment provided for the element 17. Additionally the elements 16 and 18 are both adjustable for work of different tapers, since their supporting plates or tables 24 and 38 are angularly moveable to enable the respective axes of said elements 16 and 18 to be brought into parallelism 40 with those portions or elements of the workpiece surface which are engaged by the rolls or wheels 16 and 18. In this connection, it is to be noted that said wheels or rolls 16 and 18 tend to impart by their engagement with the tapered external workpiece surface, an endwise movement to said workpiece in one direction, for example, in the arrangement shown, to the right in Fig. 2. Heretofore, in the centerless internal grinding of hollow workpieces, this endwise tendency has 45 been resisted by providing a solidly or rigidly mounted backing device adapted to be engaged by one end of the workpiece, said device serving as a fixed stop to limit such endwise movement.

50 However, I have discovered that for workpieces having tapered external peripheries, it is most desirable to resist this endwise tendency by a spring-pressed backing device bearing against the larger end of the work—such a device in this 55 particular environment serving not only to maintain the work in constant contact with the rolls 16 and 18, but also serving as a means by which slight differences in size, encountered in a run or succession of similarly-dimensioned workpieces 60 can be compensated for, in order to maintain

throughout said run, the alignment of the successive workpieces with the aforesaid gaging mechanism of the machine.

As shown in Figs. 2 and 3, the backing structure for the workpiece comprises spaced fingers 47 and 47' engageable with the end surface of the workpiece substantially on its horizontal axis and on opposite sides of a vertical plane containing said axis. Each of the fingers is separately mounted to press yieldingly against the larger end of the workpiece, thereby to maintain its contact with the rolls 16 and 18 and since the mountings are identical a description of either support will suffice for both.

Referring to Fig. 3, the finger 47 is carried by a member 49, being held in adjusted position therein by a clamping screw 50. The member 49 is turnable about a horizontal pin 51 in a block 52 mounted on the upper side of a slide 53. The slide 53 is longitudinally adjustable on a guide member 54 mounted on the top of the table 1. A coil spring 55 (see also Fig. 1) is positioned between the member 49 and the block 52, being positioned in recesses 56 and 57 in the member and block respectively. The spring thus resiliently holds the finger 47 against the end of the workpiece. An adjustable screw 58, also positioned in the member 49, limits the turning movement of the member 49 under the action of the spring when no workpiece is in position in the work-supporting structure.

A member 49', corresponding to the member 49, supports the finger 47' and this member is carried by a block 52'. A threaded rod 59 in the slide 53 has left and right hand threads thereon, as shown in Fig. 2, for engagement with threaded lugs, not shown, on the blocks 52 and 52' respectively, and thus the rod provides for simultaneous movement of the fingers 47 and 47' toward or away from each other to adjust the spacing of said fingers to workpieces of varying size.

To provide for a longitudinal adjustment of the slide 53 the guide member has mounted therein a screw 60 which operatively engages a threaded lug, not shown, on the slide. By this arrangement it is possible to adjust the position of the back rest or fingers 47 and 47' longitudinally of the table as a unit to accommodate various lengths of workpieces. The threaded rod 59, as above stated, provides for adjustment of the two fingers 47 and 47' laterally of the table to accommodate various diameters of workpieces, this lateral adjustment being independent of the longitudinal adjustment of the fingers 47 and 47'.

It frequently happens in the grinding of a succession of similarly-dimensioned workpieces that one or more of said workpieces will be slightly off-size; for example, while the workpiece *a* shown in Fig. 2 may have the precise external diameter for which the apparatus is adjusted, another workpiece in the same run or series may be slightly undersize externally,—and this condition under ordinary circumstances would involve a slight shifting of the axis of rotation of said off-size workpiece, so that its bore would not align exactly with the gaging mechanism. However, this difficulty is overcome in the present instance by the yieldability of the thrust-resisting members 47 and 47', the latter permitting such under-size workpiece to shift endwise, under the influence of the spring-urged roll 18 until true axial alignment of said workpiece with the gaging mechanism is secured. In other words,

this use of a yieldable thrust-resisting device, when such externally-tapered workpieces are being internally ground by the centerless method, makes such workpieces self-aligning with the gage mechanism, regardless of slight variations in their external diameters. The workpiece cannot be unduly displaced endwise by the spring-urged members 47 and 47', because its movement toward the left, Fig. 2 is limited by engagement of its end flange with the wheels or rolls 16 and 18.

I claim:

1. In an internal grinding machine, a centerless or chuckless means for the support and rotation of the work, comprising a plurality of circumferentially-spaced elements engageable with the periphery of a workpiece and a yieldable backing member engageable with an end surface of the workpiece, said backing member including spaced work-engaging elements adjustable toward or away from each other to accommodate various sizes of workpieces.

2. In an internal grinding machine, a centerless or chuckless means for the support and rotation of the work, comprising a plurality of circumferentially-spaced elements engageable with the periphery of a workpiece and a yieldable backing member engageable with an end surface of the workpiece, said backing member including spaced work-engaging elements adjustable toward or away from each other to accommodate various sizes of workpieces, said backing member being also adjustable toward and away from the spaced work-engaging elements to accommodate various lengths of workpieces.

3. In an internal grinding machine, a centerless or chuckless means for the support and rotation of the work, comprising a plurality of circumferentially-spaced rolls engageable with the periphery of a workpiece, means for adjusting each of said rolls toward or away from the other, and a backing member engageable with an end surface of the workpiece and comprising spaced parallel elements movable toward or away from each other to accommodate various sizes of workpieces.

4. In an internal grinding machine, a centerless or chuckless means for the support and rotation of the work, comprising a plurality of circumferentially-spaced rolls engageable with the periphery of a workpiece, means for adjusting each of said rolls toward or away from the other, each of said rolls being adjustable about an axis at right angles to the roll axis to accommodate the rolls to a workpiece having a tapering outer surface.

5. In a machine tool, the combination with a reciprocable gage adapted to enter the bore of a workpiece, of a work-supporting structure for supporting and rotating a workpiece in alignment with said gage, said structure comprising spaced rolls engageable with the periphery of the workpiece and adjustable separately toward and away from the axis of the gage to accommodate different sizes of workpieces with each workpiece supported in precise alignment with the gage, a backing member engageable with an end surface of the workpiece to limit the endwise movement relative to the rolls, said backing member comprising spaced elements adjustable toward and away from each other for accommodating different sizes of workpieces.

6. In apparatus of the class described, centerless means for the support and rotation of an-

nular workpieces having non-cylindrical outer surfaces during a machining operation on the bore thereof, said means comprising a plurality of spaced elements, at least one of which is a positive driven roll, all of said elements being engageable with the periphery of a workpiece in portions where the elements of the outer surface of the workpiece are convergent, the portions of the elements engageable with the workpiece corresponding in contour to the non-cylindrical portion of the workpiece surface, one of said elements being resiliently urged toward the others to assure an engagement between each of said elements and the workpiece, and a yieldable backing member engageable with an end surface of the workpiece away from which the elements are convergent, said backing member urging the workpiece endwise relative to the spaced elements until a flange on the workpiece engages with at least one of said elements.

7. In apparatus of the class described, centerless means for the support and rotation of annular workpieces having non-cylindrical outer surfaces during a machining operation on the bore thereof, said means comprising a plurality of spaced rolls engageable with the periphery of a workpiece, a support cooperating with said rolls and also engageable with the workpiece periphery, said rolls and support engaging the workpiece in a portion where the elements of the outer surface thereof are convergent, one of said rolls being resiliently urged toward the support and the other roll to assure an engagement between each of said rolls and the workpiece and to hold the workpiece against the support, the portions of the rolls and the support which are engageable with the workpiece corresponding in contour to the surface of the workpiece engaged thereby, and a yieldable backing member engageable with an end surface of the workpiece away from which the elements of the outer surface thereof are convergent, said backing member limiting the endwise movement of the workpiece resulting from the action of the rolls thereon.

8. In an internal grinding machine, a centerless or chuckless means for the support and rotation of hollow workpieces, each with a tapered external surface, said means including a plurality of circumferentially-spaced rotary members for engagement with said tapered workpiece surface, means for gaging each workpiece bore during the grinding operation thereon, said rotary members being radially adjustable relative to said gaging means to enable various sizes of workpieces to be supported and rotated thereby in substantial alignment with said gaging means, and means for resisting endwise movement of the workpiece by said rotary members, said last-named means being spring-pressed against one end of the workpiece, whereby any workpiece varying slightly from the external size for which the rotary members are adjusted, may shift endwise in said centerless or chuckless means to maintain its alignment with said gaging means.

9. In an internal grinding machine, a centerless or chuckless means for the support and rotation of hollow workpieces each having a tapered

external surface, said means including a plurality of circumferentially-spaced rotary members for engagement with the tapered workpiece surface, one of said members being spring-pressed against said surface, means for gaging each workpiece bore during the grinding operation thereon, said rotary members being arranged to maintain each of a succession of similarly-dimensioned workpieces in substantial alignment with said gaging means, and a yieldably-mounted member engageable with one end of each workpiece to resist endwise movement thereof by said rotary members, and cooperating with said spring-pressed rotary member to procure such endwise shifting of a slightly oversize or undersize workpiece as will establish its axial alignment with said gaging means.

10. In an internal grinding machine, a centerless or chuckless means for the support and rotation of hollow workpieces having tapered external surfaces, said means including a plurality of circumferentially-spaced rotary members for engagement with the tapered workpiece surface, the axes of said members being substantially parallel with surface elements of said workpiece, a gaging device for the workpiece bore during the grinding operation thereon, means for adjusting said rotary members to the size and degree of taper of a succession of similarly-dimensioned workpieces, to hold and rotate the latter in substantial alignment with said gaging device, and yieldable means for opposing endwise movement of such workpieces within said centerless or chuckless means, whereby the external taper of each workpiece allows any slightly undersize or oversize workpiece, by shifting endwise in said centerless or chuckless means, to maintain its axial alignment with said gaging device.

11. In an internal grinding machine, a centerless or chuckless means for the support and rotation of the work, said means including a plurality of circumferentially-spaced rolls engageable with the periphery of a workpiece, means for adjusting said rolls toward and away from each other, to accommodate them to various sizes of workpieces, means for adjusting each of said rolls about an axis substantially at right angles to its axis of rotation, to accommodate them to variously tapered workpieces, and a spring-pressed member adapted to engage one end of an externally tapered workpiece to maintain the latter's contact with said rolls.

12. In an internal grinding machine, a centerless or chuckless means for the support and rotation of hollow workpieces having tapered external surfaces, said means comprising a plurality of circumferentially-spaced rolls engageable with said tapered workpiece surface, a grinding wheel for operation on the bore of a workpiece when the latter is supported and rotated by said rolls, and means engageable with an end surface of said workpiece for yieldably resisting the latter's endwise movement by said rolls, said means maintaining said tapered surface in frictional contact with said rolls.

HAROLD L. BLOOD.
